R. E. DURNING

VALVE LOCK

Filed Aug. 2, 1924

*ROBERT E. DURNING,
INVENTOR.*

BY William A. Hartle;

Attorney.

UNITED STATES PATENT OFFICE.

ROBERT E. DURNING, OF BELLEVUE, PENNSYLVANIA.

VALVE LOCK.

Application filed August 2, 1924. Serial No. 729,835.

To all whom it may concern:

Be it known that I, ROBERT E. DURNING, a citizen of the United States of America, residing at Bellevue, in the county of Allegheny and State of Pennsylvania, have invented certain new and useful Improvements in Valve Locks, of which the following is a specification.

The present invention relates to a means for locking the gasoline pipe line which ordinarily leads from the gasoline storage reservoir or tank to the carburetor on automobiles, and has for its object the provision of a means which may be locked with a "Yale" type of lock. As is well known in trade, the said type of lock last named possesses a valuable feature in connection with its use for locking the gasoline supply of an automobile, on account of the difficulty of obtaining a duplicate key that will unlock the "Yale" lock, and as a consequence the said supply of gasoline is prevented from reaching the carburetor of the engine, as is at once appreciated.

As will be seen as the description proceeds herein, I have provided a very simple arrangement of parts which accomplish the end sought directly, and efficiently, with no complicated parts liable to get out of order, and as a corollary, it is believed such a locking means will appeal to the average owner of an automobile on account of its simplicity in parts as well as its operation.

In the accompanying drawings forming part of the present specification, I have illustrated a complete example of the invention in hand, constructed according to the best mode I have so far devised for the practical application of the principles of my invention.

In the drawings Figure 1 is a longitudinal section taken centrally thereof, of my invention applied to a pipe line.

Figure 2 is a view of Figure 1, taken in elevation, and partly in section, looking from the left of said Figure 1.

Figure 3 is a plan view of Figure 1.

Figure 4 is a partial horizontal section of a feature of the device, taken on line 4-4 of Figure 2.

The numeral 1 indicates in the drawings an ordinary "two-way" (or if preferred "four-way") valve, mounted on the gasoline line of piping 2 leading from the gasoline reservoir (not shown) of an automobile, and said valve which is usually of the

"globe" type is connected to the pipe 3 which in turn leads to the carburetor of the engine (not shown in the drawings). It is apparent from the figures shown that if the valve 1 cannot be operated by unauthorized persons, as will be explained, that the supply of gasoline cannot reach the engine, and as a result the automobile cannot be operated, and theft is impossible.

The valve 1 has a stem 4, which is formed cylindrical in shape, and same has a passage therethrough, for the purpose of admitting a locking slug or key 6 as shown in Figure 1. The part 4 has a prong 7 which engages the stops 8 and 9 in order to limit the travel of the valve stem 4. The valve 1 is completely enclosed by the casing 11, which is suitably mounted on the beams, (or other parts) 12, 13, etc., of the automobile. The casing has an upstanding U-shaped part 14, which is provided with a transverse perforation 15, and the key 6 has a cutaway portion 16 formed complementary to the said perforation 15, both being adapted to receive the lock ring 10 of the lock 17, which last is preferably of the "Yale" type of lock. The casing 11 has mounted therein the tubular part 18, which may be a driven fit into the neck 19 of the casing 11, or threads 85 may be provided at 20, in order to secure the tube 18 in position. The said tube 18 has a slot 21 which is approximately one-quarter the length of its circumference, as is seen in Figures 1 and 2 of the drawings, 90 the purpose of said slot it is seen is to accommodate the transverse bolt or pin 22.

The said pin 22 passes through the tubular part 18, and also through the valve stem drum 4, and forms a means of supporting said valve stem drum in the tube 18, and the casing neck 19. The end 23 of the pin 22, is extended and preferably threaded, so that a handle similar to handle 24 suitably modified with a female thread may be attached to said pin, and thus provide a means of rotating the valve stem 4, if desired. When such use is not required, the end 23 is sheared even with the exterior of the tube 18.

The pin 7 is mounted in the drum 4, and the stops 8 and 9 are mounted in the inner side of the casing 11, as is at once understood from the drawings. The pipes 2 and 3 are suitably connected at 25, 26 respectively by couplings to the valve 1 as shown, said couplings being completely within the

17 casing 11, and cannot be reached surreptitiously in any way, as the said casing is
 18 provided with a bottom plate 27. The bottom plate is fastened by the screws 28, 28
 19 to the inwardly disposed lugs 29, 29 integrally formed with the casing 11. The
 20 casing 11 is preferably attached to channels
 21 12, 13 which are a part of the automobile
 22 by means of the riveted lugs 30, 30, etc.
 23 It is seen from Figure 2, that the bottom
 24 plate 27 cannot be removed, on account of
 25 being superimposed on the beams or floor
 26 of the automobile, and the casing held down
 27 by the riveted lugs 30. The key or slug
 28 6 has a chain 31 attached at 32 to same, the
 29 other end of said chain being preferably attached
 30 to the screw-ring 33, to prevent said
 31 key being lost when the automobile is in
 32 use, and it will be noted that the perfora-
 33 tion 34 is made in the casing 11, in order
 34 to place said key in the chamber of said
 35 casing when desired.

36 The preferred way of moving the valve
 37 stem drum 4 is by means of the handle 24,
 38 which is provided with a stem 35, the inner
 39 end 36 of which engages slidably a recess
 40 formed for it in the drum 4, as illustrated
 41 in detail in Figure 4 of the drawings. On
 42 the said handle stem is the collar 37 which
 43 is preferably formed integral therewith,
 44 and against which the coil spring 38 bears
 45 as shown. The spring 38 also bears against
 46 the inner wall of the casing neck 19 as
 47 shown. It is evident that the handle can
 48 reciprocate in the slot 39 when the handle
 49 24 is manually operated to overcome the
 50 spring 38, and as a result the prongs 40,
 51 40 can be disengaged from their recesses
 52 41, 41 formed in the outer wall of the cas-
 53 ing 19, for a purpose to be described. The
 54 casing neck it will be noted has a recess or
 55 slot 42, so that the handle stem 35, can
 56 travel therein, and operate the valve stem
 57 drum 4. When the key 6 is removed from
 58 the valve stem, as seen in Figure 3, the
 59 handle 24, can be disengaged from the
 60 notches 41, and the valve stem rotated from
 61 point 43 to 44, or vice versa; thus opening
 62 or closing the valve 1 as may be desired.
 63 The said notches or recesses 41, 41 provide
 64 a means of holding the valve open or shut
 65 without manually holding the handle 24.

66 The operation of the device in hand is as
 67 follows. As seen from the Figure 1 of the
 68 drawings the valve 1 is in locked position
 69 with the key or slug 6 passing through the
 70 upstanding part 14, the casing neck 19, the
 71 tube 18 and the valve stem drum 4; the
 72 ring of the Yale lock 17 being in position
 73 and preventing the removal of the slug 6
 74 from said valve stem. When it is desired to
 75 use the automobile, the Yale lock is
 76 removed, the key 6 taken out and placed in
 77 the chamber of the casing 11. The handle
 78 24 is then disengaged from the notches at

79 44, and rotated to the position shown in
 80 Figure 3, and in engagement with notches
 81 at 43. Gasoline can then pass through the
 82 valve 1 to the pipe 3, and to the carburetor
 83 of the engine, as before explained. When 70
 84 the trip is concluded the handle 24 is swung
 85 back to point 44, the slug 6 replaced through
 86 the valve stem as in Figure 1, the Yale
 87 lock replaced in position to lock same, and
 88 the automobile is safe against unauthorized 75
 89 operation.

90 It is noted in passing that the valve may
 91 be made a "four-way" valve with addi-
 92 tional pipes 45, 46 entering the casing and
 93 leading to other parts of the engine, as has
 94 been found desirable in connection with the
 95 use of a vacuum tank and other devices in
 96 some instances, but as this is a matter which
 97 pertains to the valve per se rather than the
 98 locking device in hand, same will not be 85
 99 more fully described in this place.

100 From the above it is evident that I have
 101 provided a very useful device, which is ex-
 102 ceedingly simple in the parts, and use, and
 103 yet is certain to accomplish the much de-
 104 sired result of preventing theft of automo-
 105 biles, as it is a commonly known fact that
 106 automobile theft is accomplished at the
 107 present time, by duplication of the keys nec-
 108 essary to unlock the locks in current use 95
 109 on automobiles.

110 I claim:—

111 1. In a valve lock, a valve, an enclosing
 112 casing having an upwardly disposed neck,
 113 and a U-shaped member formed thereon pro-
 114 vided with transverse perforations, a valve
 115 stem drum rotatably mounted in the cas-
 116 ing neck, a locking key having a recess
 117 formed complementary to the U-shaped
 118 member perforations, and locking means 105
 119 passing through said key and U-shaped
 120 member for holding the key in locked po-
 121 sition.

122 2. In a valve lock, a valve, an enclosing
 123 casing having an upwardly disposed neck,
 124 a tubular member mounted in the latter, a
 125 valve stem drum revolvably mounted in the
 126 tubular member, a U-shaped member hav-
 127 ing transverse perforations formed on the
 128 casing, a locking key passing through the
 129 casing neck, the tubular member, and the
 130 valve stem drum, and means for securing
 131 the said locking key in locked position.

132 3. In a valve lock, a valve, a casing en-
 133 closing the valve and pipe connections lead-
 134 ing to and from said valve, an upwardly
 135 disposed tubular neck formed on said cas-
 136 ing provided with a horizontal passage, a
 137 peripheral slot, and a number of notched
 138 recesses in its side wall, a U-shaped member
 139 having transverse perforations there-
 140 through formed on the casing, a valve stem
 141 drum rotatably mounted in the tubular neck
 142 and having a horizontal passage through it
 143 adapted to register with the horizontal pas- 130

sage through the tubular neck, a handle for operating the valve stem drum reciprocably mounted in the latter, a pair of prongs on the handle adapted to engage the notched recesses of the casing neck, resilient means for holding said prongs in engaged positions in the notched recesses, a key having a recess formed complementary to the U-shaped member perforations, passing through the casing neck and valve stem horizontal passages, and locking means for the key adapted to engage the perforations of the U-shaped member and the complementary recess of the key, for locking said key in position.

4. In a valve locking device, operating means comprising a tubular casing neck having a horizontal slot in its periphery, and a plurality of notched recesses on its outer wall, a tubular member mounted in the casing neck having a peripheral slot formed complementary to the slot of the casing neck, a valve stem drum rotatably mounted in the tubular member and having a radial depression formed therein, an operating handle having a pair of prongs adapted to engage aforesaid notched recesses, a collar on the handle, and a resilient spring engaging the collar, and the inner wall of the casing neck for resiliently holding the handle in reciprocating position in the radial depression of the valve stem drum.

5. In a valve lock, a valve, an enclosing casing covering said valve and pipe connections thereto, an upwardly disposed casing neck on the casing, a tubular member mounted in the casing neck having a peripheral slot, a valve stem drum revolvably mounted in the tubular member and having a pin passage therethrough, a transverse pin passing through the drum and in engagement with the peripheral slot of the

tubular member, a locking key passing through the casing neck the tubular member and the valve stem drum, and means for locking said key in position.

6. In a valve lock, a valve, an enclosing closing having a neck formed thereon, a valve stem drum revolvably mounted in the casing neck, a U-shaped member on the casing, a locking key having a recess formed therein, passing through the U-shaped member, the casing neck and the valve stem drum, and means for locking said key in position.

7. In a valve lock, a valve, an enclosing casing, having a casing neck formed thereon, an upper horizontal peripheral slot in the casing neck, a U-shaped member on the casing, a valve stem drum mounted in the casing neck, a transverse pin carried in the valve stem drum, slidably engaging the casing neck horizontal slot, a reciprocating locking key, passing through the U-shaped member, the casing neck, and the valve stem drum, and means for locking the said locking key in position.

8. In a valve lock, a valve, an enclosing casing covering said valve and pipe connections thereto, a casing neck on the casing, an upper horizontal peripheral slot in the casing neck, a valve stem drum revolvably mounted in the casing neck, a transverse pin forming a turning means, mounted in the valve stem drum, and adapted to operate in the horizontal casing neck slot, a locking key engaging the casing neck and the valve stem drum, and means for locking the key in position.

In testimony whereof I affix my signature.

ROBERT E. DURNING.
